AUTO-SHAPED DEEP SEAT FOR PLAYGROUND APPARATUS

Ronald W. Zick, Minneapolis, Minn., assignor to The
Toro Company, Minneapolis, Minn.

Filed Mar. 24, 1975, Ser. No. 561,316

Term of patent 14 years

Int. Cl. D21—03

U.S. Cl. D34—5 L

FIG. 1

FIG. 4

FIG. 2

FIG. 5

FIG. 3

FIG. 7

FIG. 6

FIG. 1 is a perspective view of an auto-shaped deep seat for playground apparatus embodying my new design;

FIG. 2 is a right side elevational view thereof on a reduced scale;

FIG. 3 is a left side elevational view thereof on a reduced scale;

FIG. 4 is a front elevational view thereof on a reduced scale;

FIG. 5 is a rear elevational view thereof on a reduced scale;

FIG. 6 is a top plan view thereof on a reduced scale; and

FIG. 7 is a bottom plan view thereof on a reduced scale.

I claim:

The ornamental design for an auto-shaped deep seat for playground apparatus, as shown.
